UNITED STATES PATENT OFFICE.

THOMAS GILBERT BOWICK, OF LONDON, ENGLAND.

DESIGN FOR A MOTOR-FLOAT.

SPECIFICATION forming part of Design No. 29,151, dated August 2, 1898.

Application filed December 29, 1897. Serial No. 664,480. Term of patent 14 years.

To all whom it may concern:

Be it known that I, THOMAS GILBERT BOWICK, a subject of the Queen of England, residing at London, England, have invented and 5 produced a certain new and original Design for a Motor-Float, of which the following is a specification.

My design for a motor-float is shown in side elevation in Figure 1 and in cross-section in 10 Fig. 2 on the line 2 2 of Fig. 1.

My design consists of an elongated body 1 of substantially rounded or cylindrical cross-sectional form and with tapered ends 2 3, as shown in Fig. 1. The elongated body is 15 mounted by a body 3, having rounded lateral

sides, with a curved neck at the front surmounted by a head portion 4 and having wing portions 5 and a tail portion 6. The said upper body is mounted centrally of the lower elongated body. 20

I claim as my invention—

The design for a motor-float herein shown and described.

In witness whereof I have hereunto set my hand in presence of two witnesses.

T. GILBERT BOWICK.

Witnesses:

VICTOR F. FEENY,
WALTER J. SKERTEN.
